UNITED STATES PATENT OFFICE.

EDWIN G. NICEWANER, OF JOHNSTOWN, PENNSYLVANIA, ASSIGNOR TO THE LORAIN STEEL COMPANY, OF PENNSYLVANIA.

CAR-TRUCK.

SPECIFICATION forming part of Letters Patent No. 639,274, dated December 19, 1899.

Application filed June 19, 1899. Serial No. 721,162. (No model.)

To all whom it may concern:

Be it known that I, EDWIN G. NICEWANER, of Johnstown, in the county of Cambria and State of Pennsylvania, have invented a new and useful Improvement in Car-Trucks, of which the following is a full, clear, and exact description, reference being had to the accompanying drawings, which form a part of this specification.

10 This invention relates generally to car-trucks, and more particularly to that class of trucks which employ an independent frame spring-supported from and below the axle or journal boxes. In this class of trucks as heretofore constructed it has been a matter of more or less difficulty to remove the axle-boxes, wheels, and axles from the truck, owing to the manner in which the axle-boxes have been mounted; and the object of the present 15 invention is mainly to provide simple means whereby this difficulty is overcome and the boxes, axles, and wheels may be readily and easily removed. I attain these objects by the means which I will now proceed to describe, 20 reference being had to the accompanying drawings, in which—

Figure 1 is a side elevation showing one of the boxes mounted in accordance with the invention. Fig. 2 is an end view of one of the 25 yokes or stirrups detached, and Fig. 3 a side view of a truck in which the invention is embodied.

In the drawings, the letter A designates one of the side bars of a truck of the class above indicated and which is provided with open-top guides or pedestals A' rising therefrom for the axle-boxes B.

D D designate rigid yokes or stirrups whose side arms loosely straddle or embrace the respective pedestals or guides and are pivotally secured to the lower end portions in seats E, formed between the pedestals or guides and hinge butts or lugs E', said end portions, the pedestals or guides, and the stirrup-arms being provided with registering perforations d' d² for the pins or pivots d³. The latter may have inner headed ends countersunk in the pedestals or guides, as indicated at d⁴ in Fig. 4, and their outer ends may be secured by

cotter-pins d⁵. These, however, are mere mechanical details, to which the invention is in no way restricted. The manner in which the stirrup is pivoted permits it to be swung laterally over the side frame of the truck entirely clear of the axle-boxes.

G G designate the axle-box springs, which are seated at their lower end portions in pockets on the axle-boxes and at their upper ends in inverted pockets G', formed in the transverse or connecting portions of the yokes or stirrups.

H designates the bolster, and I the vehicle-body-supporting springs. These, however, form no part of the invention.

In order in the constructions above described to remove the axles, wheels, and boxes from the frame A, it is necessary only to jack up the said frame sufficiently to take the compression off the springs G. The yokes or stirrups D can then be swung laterally and outwardly, leaving the top of the pedestals unobstructed. The axles can then be lifted out and removed.

I do not wish to limit myself to the details of construction which I have herein shown and described, as these may obviously be varied in many respects without affecting the character and scope of my invention. Nor do I limit myself to the use of the invention upon the particular style of truck which is illustrated.

Having thus described my invention, what I claim, and desire to protect by Letters Patent, is—

1. In a car-truck, the combination with a frame having open-top pedestals for the axle-boxes, and laterally-open seats at the bases of said pedestals; of spring caps or pockets and yokes or stirrups supporting the said caps or pockets and pivotally secured at their lower ends in said open seats.

2. In a car-truck, the combination with an open-top pedestal and an axle-box seated therein of a yoke or stirrup embracing the said pedestal and pivoted to move laterally thereof.

3. In a car-truck, the combination with the spring-supported side bar having open-top

guides or pedestals, of the yokes or stirrups embracing said guides or pedestals, and having spring-pockets normally above the same, and pivotal connections between said guides or stirrups and the side bar.

4. In a car-truck, the combination with a side bar spring-supported below the axle-boxes and supporting the vehicle-body, said bars having open-top pedestals or guides for the axle-boxes, and adjacent thereto hinge butts or lugs, of yokes or stirrups straddling or embracing the said pedestals or guides and provided with spring-pockets normally over the axle-boxes, and hinge or pivot pins seated in the said pedestals and hinge-butts, and

passing loosely through said yokes or stirrups at their lower ends.

5. In a car-truck, the combination of a side frame having pedestals, journal-boxes seated in said pedestals, springs seated on said boxes, and rigid yokes or stirrups pivoted to said side frame at the outer sides of the pedestals to swing laterally therefrom and seating the upper ends of the said springs.

In testimony whereof I have affixed my signature in presence of two witnesses.

EDWIN G. NICEWANER.
